UNITED STATES PATENT OFFICE.

EDWARD E. BUSEK, OF MILWAUKEE, WISCONSIN, ASSIGNEE, BY MESNE ASSIGNMENTS,
TO HEMPHILL MANUFACTURING COMPANY, OF PAWTUCKET, RHODE ISLAND, A
CORPORATION OF RHODE ISLAND.

KNITTING-MACHINE

1,204,404.

Specification of Letters Patent. Patented Nov. 14, 1916.

Application filed December 15, 1913. Serial No. 806,733.

To all whom it may concern:

Be it known that I, EDWARD E. BUSEK, a citizen of the United States, residing at Milwaukee, in the county of Milwaukee and 5 State of Wisconsin, have invented certain new and useful Improvements in Knitting-Machines, of which the following is a specification, reference being had to the accompanying drawing, forming a part thereof.

10 This invention relates to knitting machines and the objects of the invention are to improve circular knitting machines so that the action of the droppers in widening the part of the fabric being knitted may include the needles with the long butts in addition to the needles with the short butts.

Referring to the drawings which accompany this specification and form a part hereof, which drawings illustrate an embodiment of this invention, and on which drawings the same reference characters are used to designate the same elements wherever they may appear in each of the several views, Figure 1 is a front elevation of part 25 of an automatic, circular knitting machine; Fig. 2 is an elevation of the left hand side of the parts of the machine illustrated by Fig. 1; Fig. 3 is a sectional view, drawn to an enlarged scale, taken on the line *a—a* 30 on Fig. 1, looking in the direction indicated by the arrows; and Fig. 4 is an elevation, on the same scale as Fig. 3, of cam mechanism.

The invention which is to be described in 35 this specification is illustrated by the drawings in connection with a well-known make of automatic, circular knitting machine, the construction of which does not need to be described in detail herein as reference may 40 be had for such details to United States Letters Patent Nos. 933,443, 934,969 and 1,015,733 granted to Joshua D. Hemphill on September 7, 1909, September 21, 1909 and January 23, 1912, respectively.

45 The machine may be briefly described as comprising a frame 1, drive shaft 2, crank 3, loose pulley 4, drive pulleys 5 and 6, needle cylinder 7, cam shaft 8, stop-motion wheel 9, pattern chain 10, chain wheel 11, main ratchet 12, pawl supporter 13, cam-wheel 14, sliding bar 15, cam-plate 16, knitting-cam-member 17, pickers 18 and 19, droppers 20 and 21, and belt shipper 22, all of which 50 operate in the same manner and for the same

purposes as the same parts illustrated and 55 described in the Letters Patent hereinbefore referred to, except the angular oscillations of the needle cylinder 7 are increased to about a fourth more than a complete revolution.

About half of the needles have long butts 23 and the other half have short butts 24 and when the needle cylinder is being continuously revolved or rotated to knit with all the needles, the butts of all the needles 60 are down to the base cam 25 in the ordinary manner.

The cam 26, which only projects into the path of the long butts 23, and which can be moved up and down in the guide 27, is 65 the lifting cam for elevating or lifting the needles with the long butts to throw them out of knitting action. This cam is lifted by the cam surfaces which project from the cam-drum 28 in the path of the cam follower 70 29 and is lowered by the spring 30 when the said cam surfaces permit, in a manner which will be readily understood. The lifting cam 26 is connected with cam follower 75 29 by the links 31 and 32 and lever 33. The 80 cam 34, which projects into the path of the butts of all the needles, and which can be moved up and down in the guide 27 independently of the lifting cam 26, is the lowering cam for bringing the elevated needles 85 down into knitting positions. This lowering cam is lifted by the cam surfaces which project from the cam-drum 28 in the path of the cam follower 35 and is lowered or depressed by the spring 36. The lowering 90 cam 34 is connected with cam follower 35 by the links 37 and 38 and the lever 39. The levers 33 and 39 are illustrated as pivoted to a bracket 40 which is secured to the frame 1 and the guide 27 is illustrated as 95 secured to the cam-plate 16.

With the construction illustrated and described the lifting and lowering cams should move up, or lift, together but the lifting cam 26 should move down independently of the 100 lowering cam and long enough before the lowering cam 34 moves down to allow the droppers to drop the number of needles desired. It is evident that if the droppers began to drop or pick down needles with 105 the long butts while the lifting cam 26 remained in its elevated position, the lifting cam would immediately lift the needles with

the long butts out of knitting position thereby defeating the result desired. Figs. 2 and 3 of the drawings clearly illustrate the independent, timed lowering movements of the lifting cam 26 and the lowering cam 34 permitted by the cam surfaces in the paths of cam followers 29 and 35 on cam-drum 28.

It will be understood, of course, that the machine can be adjusted for the particular work to be done as is customary with these machines, and, for the purpose of illustration, the operation of the machine will be described while knitting enough of a sock to make this invention readily understood.

The leg of the sock is knitted with the needles and their butts all down. When the fashion chain 10 has been moved the distance necessary to correspond with the pre-determined length of the leg, the mechanism moves cam-drum 28 and elevates simultaneously the lifting cam 26 and the lowering cam 34. While the leg is being knitted the needle cylinder 7 is being rotated continuously but with the lifting of the lifting and lowering cams the motion of the needle cylinder changes from a continuous rotation to a back and forth oscillation and the lifting cam 26 lifts all the needles with the long butts throwing them out of the knitting action. As the needle cylinder oscillates, the pickers 18 and 19 alternately pick up a needle in the ordinary manner to narrow the part being knitted and this action continues for such a time, or number of rows of stitches, as is determined by the pattern chain. Then the mechanism starts the droppers 20 and 21 into action to alternately drop or lower two needles at a time to widen the part being knit. It is understood, of course, that the needle cylinder is still oscillating and the pickers 18 and 19 are still picking up single needles. The lifting cam 26 is now lowered by the mechanism at the time determined by the fashion chain and the only point to be observed is that the lifting cam is lowered before the droppers begin to drop or pick down the needles with the long butts. The machine can now be run continually widening the part being knitted as long as desired, say until about three-fourths of the needles are down and knitting. This knitting is timed by the fashion chain and when the fashion chain causes the mechanism to move to permit the lowering cam 34 to be pulled down by its spring, this cam will be pulled down and will lower or depress all the needles remaining elevated, the needle cylinder will cease oscillating and will revolve continuously to knit the foot of the sock.

What is claimed is:—

1. In a circular knitting machine, the combination of a needle cylinder, needles having short

butts carried thereby, a knitting cam member, narrowing pick mechanism, widening pick mechanism, a lifting cam adapted to contact only with the needles having long butts, a lowering cam for said needles, 70 means for lifting said lifting and lowering cams to elevate the needles having long butts and means for lowering the lifting cam before the lowering cam is lowered to permit the widening pick mechanism to pick down 75 needles having long butts into knitting position without said needles being interfered with by either of said cams.

2. In a circular knitting machine, the combination with a needle cylinder and 80 needles having long butts and needles having short butts carried thereby, a knitting cam member, narrowing pick mechanism, widening pick mechanism, a guide, a lifting cam and a lowering cam supported by 85 said guide, said lifting cam being adapted to contact only with the needles having long butts and cam mechanism for lifting the lifting and lowering cams and retaining the said cams in elevated position, the cam mechanism being adapted to retain the lowering cam in an elevated position after the lifting cam has been lowered to permit the widening pick mechanism to pick down needles 90 having long butts into knitting position 95 without said needles being interfered with by either the lifting cam or the lowering cam.

3. In combination in a stocking knitting machine, a needle cylinder, needles arranged 100 in two series, one having longer butts than the other, stitch cams, a cam for elevating the longer butt needles in making heel and toe pockets on the shorter butt needles, narrowing pick mechanism, and widening pick 105 mechanism operating upon both the short and the long butt needles to widen the fabric beyond the point where narrowing began.

4. In combination in a stocking knitting machine, a needle cylinder, needles arranged 110 in two series, one having longer butts than the other, a cam for lowering the longer butt instep needles to normal plane, a cam operating automatically and independently of the said lowering cam to raise the longer 115 butt instep needles to inoperative position, and narrowing and widening pick mechanism, said widening pick mechanism being operative upon both the short and the long butt needles to widen the fabric beyond the 120 point where narrowing began, substantially as described.

5. In combination in a stocking knitting machine, a needle cylinder having rotary and reciprocating movements, needles in two 125 series, one having longer butts than the other, an instep cam for raising the longer butt needles to inoperative position, narrowing and widening pick mechanisms, said widening pick mechanism being operative 130

upon both the short and long butt needles to continue widening beyond the point where narrowing began, means for operating the instep cam to position for raising 5 the instep needles, and to retract it before widening begins on the longer butt needles, substantially as described.

6. A knitting machine having in combination a needle cylinder provided with instep needles and heel needles, stitch cams, a cam for moving the instep needles to inoperative position at the beginning of a heel, narrowing pick mechanism to act upon the heel needles, widening pick mechanism, 10 means for causing said widening pick mechanism to act on the heel needles, and also upon a number of the instep needles, and a restoring cam for restoring the remainder of the instep needles to operative position.

20 7. A knitting machine having in combination a needle cylinder provided with instep needles and heel needles, stitch cams, a cam for moving the instep needles to inoperative position at the beginning of a heel, narrowing pick mechanism to act upon the heel needles, widening pick mechanism, means for causing said widening pick mechanism to act upon the heel needles and also upon a number of the instep needles, a restoring 25 cam for restoring the remainder of the instep needles to operative position and means for operating said first mentioned cam independently from said restoring cam.

8. A knitting machine having in combination a needle cylinder provided with instep needles and heel needles, stitch cams, a needle raising cam, means for actuating said cam to move the instep needles to inoperative position at the beginning of the heel, narrowing pick mechanism to act upon the heel needles, widening pick mechanism, 30 means for causing said widening pick mechanism to act upon the heel needles and also upon a number of the instep needles, a restoring cam for restoring the remainder of the instep needles to operative position, and means for returning said needle raising cam to normal position before the widening pick mechanism begins to act upon the instep 35 needles.

50 9. In combination in a stocking knitting machine, a needle cylinder, a needle cam carrier, one of said parts having rotary and reciprocatory movements, instep needles, heel and toe needles, means for throwing all the instep needles out of operation as a

group for formation of the heel, narrowing pick mechanism for narrowing the heel pouch by throwing out of operation heel and toe needles only, and widening pick mechanism for subsequently widening the heel pouch, said rotary and reciprocating part continuing its reciprocations and said widening pick mechanism continuing its picking operations on the instep needles 60 originally rendered inoperative as a group and beyond the point where narrowing began, substantially as described.

10. In combination in a stocking knitting machine a needle cylinder, heel and toe and instep needles, knitting cams, a vertically movable needle restoring cam to engage the instep needle butts for lowering them to operative position, automatically operating connections for moving said needle restoring 70 cam vertically to different positions, an automatically operated vertically movable needle raising cam for raising instep needles and narrowing and widening pick mechanism, the latter continuing the widening beyond the point where narrowing began and connections automatically operating independently of the first mentioned connection for operating the needle raising cam and lowering it before the continued widening of 80 the fabric takes place, substantially as described.

11. In combination in a stocking knitting machine, a needle cylinder, heel and toe and instep needles, knitting cams, a vertically 90 movable needle restoring cam to lower the instep needles to operative position, automatically operating connections for moving said cam to different positions, a needle raising cam to elevate instep needles to inoperative position, narrowing pick mechanism, widening pick mechanism, the latter performing additional widening actions beyond the point where narrowing began for the heel, and automatically operating connections, independent of those first mentioned for operating the needle raising cam to position for raising the needles and restoring said cam to normal position before the additional widenings are performed, substantially as described.

In witness whereof I hereto affix my signature in presence of two witnesses,

EDWARD E. BUSEK.
